UNITED STATES PATENT OFFICE.

EDWARD W. GOODWIN, OF DETROIT, MICHIGAN.

DESIGN FOR AN INSTRUMENT-BOARD FOR MOTOR-VEHICLES.

53,630.

Specification for Design.

Patented July 22, 1919.

Application filed April 5, 1919. Serial No. 287,831. Term of patent 14 years.

To all whom it may concern:

Be it known that I, EDWARD W. GOODWIN, a citizen of the United States, residing at Detroit, in the county of Wayne and State of Michigan, have invented a new, original, and ornamental Design for Instrument-Boards for Motor-Vehicles, of which the following is a specification, reference being had to the accompanying drawing, forming part thereof.

Copies of this patent may be obtained for five cents each, by addressing the "Commissioner of Patents, Washington, D. C."

In the drawing, the figure is a perspective view of an instrument board for motor vehicles showing my new design.

I claim:

The ornamental design for an instrument board for motor vehicles, as shown.

In testimony whereof, I hereunto affix my signature.

EDWARD W. GOODWIN.
